CLAIM

The ornamental design for a golf club and golf ball cleaning device, as shown and described.

DESCRIPTION

FIG. 1 is a perspective view of the golf club and golf ball cleaning device, in accordance with a preferred embodiment of the present invention;

FIG. 2 is an exploded perspective view of the golf club and golf ball cleaning device, as shown in FIG. 1;

FIG. 3 is a front elevational view of the golf club and golf ball cleaning device, as shown in FIG. 1, with the back elevational view being a mirror image thereof;

FIG. 4 is a left side elevational view of the golf club and golf ball cleaning device, as shown in FIG. 1;

FIG. 5 is a right side elevational view of the golf club and golf ball cleaning device, as shown in FIG. 1;

FIG. 6 is a top plan view of the golf club and golf ball cleaning device, as shown in FIG. 1; and,

FIG. 7 is a bottom plan view of the golf club and golf ball cleaning device, as shown in FIG. 1.
